DESIGN FOR A MEMORIAL PLAQUE OR SIMILAR ARTICLE

David Bank, Minneapolis, Minn.

Application July 30, 1934, Serial No. 52,733

Term of patent 14 years

To all whom it may concern:

Be it known that I, David Bank, a citizen of the United States, residing at Minneapolis, in the county of Hennepin and State of Minnesota, have invented a new, original, and ornamental Design for a Memorial Plaque, or Similar Article, of which the following is a specification, reference being had to the accompanying drawing, forming part thereof.

The figure is a plan view of a memorial convex

plaque having no appreciable thickness, showing my design which resides in two six-point stars, a candle-stick with seven candles, two lions on scroll work back of the star, an open space for the name to be engraved, and the words "In Memory" on background.

I claim:

The ornamental design for a memorial plaque, or similar article, as shown and described.

DAVID BANK.
